UNITED STATES PATENT OFFICE.

JOHN HOLYOKE BARNES, OF NORWICH, CONNECTICUT.

RAILWAY TIE.

Application filed October 12, 1922. Serial No. 594,152.

To all whom it may concern:

Be it known that I, JOHN H. BARNES, a citizen of the United States, and a resident of Norwich, in the county of New London 5 and State of Connecticut, have invented a new and Improved Railway Tie, of which the following is a full, clear, and exact description.

This invention relates to improvements in 10 railway ties, and has particular reference to a metallic tie.

An object of the invention is to provide a tie wherein rail supporting or bearing blocks are secured upon the body portion of 15 the tie in such manner that the same may be readily removed and replaced when worn, thus obviating the necessity of replacing the entire tie.

Another object is to provide an effective 20 lock for securing the bearing blocks in operative position on the tie.

The above and other objects will appear more clearly from the following detail description, when taken in connection with the 25 accompanying drawing, which illustrates a preferred embodiment of the inventive idea.

In the drawings—

Figure 1 is a partial top plan view of the 30 railway tie constructed in accordance with the invention;

Figure 2 is a side elevation thereof; and

Figure 3 is a section on the line 9—9 of 35 Figure 2.

In the embodiment of the invention illustrated in the accompanying drawing the base 40 11 is provided with the central reinforcing rib 12 and with intermediate and end abutments 13 and 14 at each end thereof. The inner opposed faces of the abutments 13 and 14 are disposed in vertical planes and the abutments are provided with overhanging flanges 28 and 29 respectively, which provide means for preventing vertical movement of the bearing block 30. In the present instance this block is placed in position on the

tie by inserting the same from the side of the tie into the recess formed by the abutments 13 and 14. The bottom surface of the bearing block 30 and the upper surface of the base 11 are provided with cooperating grooves 31 and 32, which are aligned to form an opening for receiving the locking bolt 33, the head 34 of which engages both the bearing block 30 and base 11, while the threaded portion of the bolt has mounted thereon a washer 35 engaged by a lock nut 36 to maintain the bolt in locking position. From this construction it will be apparent that the bearing blocks may be readily and quickly removed from the tie by disengaging the locking bolts therefrom.

What is claimed is:

1. A railway tie comprising a base, end and intermediate abutments, a bearing block positioned between said abutments, and a locking device interposed between said bearing block and base at a point intermediate of said abutments and having a portion overlapping said base and block for maintaining the latter in position.

2. A railway tie comprising a base, end and intermediate abutments, a bearing block positioned between said abutments, said bearing block and base having cooperating grooves to form an opening extending transversely thereof, and a locking device insertable into said opening and engageable with said base and block for maintaining the latter in position.

3. A railway tie comprising a base, abutments thereon, a bearing block positioned between said abutments, a bolt interposed between said base and block and extending transversely thereof and having a head on one end overlapping portions of said base and block, and means on the opposite end of said bolt for attaching the same to said base and block.

JOHN HOLYOKE BARNES.
